UNITED STATES PATENT OFFICE.

EASON L. SLOCUM, OF PAWTUCKET, RHODE ISLAND.

AUXILIARY FIRE ALARM AND EXTINGUISHER SYSTEM.

SPECIFICATION forming part of Letters Patent No. 449,829, dated April 7, 1891.

Application filed January 14, 1889. Serial No. 296,371. (No model.)

To all whom it may concern:

Be it known that I, EASON L. SLOCUM, a citizen of the United States, residing at Pawtucket, in the county of Providence and State 5 of Rhode Island, have invented certain new and useful Improvements in Auxiliary Fire Alarm and Extinguisher Systems, of which the following is a description, reference being had to the accompanying drawings, which 10 form a part of this specification.

The object of my invention is to provide a system of alarm-bells to be distributed in the several departments of a building in which my auxiliary stations may be placed, 15 which may be operated either by pressure upon the disk of the alarm-box or automatically; also, to provide in addition a connecting system of water-pipes and distributing-heads, by means of which any department of 20 the building can be flooded with water.

Figure 1 represents a front elevation of the internal mechanism of the auxiliary-alarm-station box. Fig. 2 represents a vertical section taken in the line $\alpha\alpha$ of Fig. 1. Fig. 3 25 represents a vertical section taken in the line $\gamma\gamma$ of Fig. 1, showing an open electric circuit to the general-alarm station. Fig. 4 represents a detail horizontal section, taken in the line $z z$ of Fig. 2, showing the contact-spring. Fig. 5 represents a front elevation 30 of the auxiliary fire-alarm box. Fig. 6 represents a vertical section, as in Fig. 3, but showing the general-alarm circuit as closed. Fig. 7 represents a plan view of the spring employed for holding the operating-disk. Fig. 35 8 represents a sectional view showing the several floors of a three-story building with my improved auxiliary fire-alarm system complete for each story, and also showing the general-alarm station attached to a lamp-post and 40 electrically connected with the auxiliary stations located in the building.

Referring to the drawings, the alarm-operating metal disk a rests in a caliper-formed 45 spring b , which is firmly attached to the front of the station-box. The slot b' of this spring allows of sufficient play in its arms to receive and firmly hold the disk, being constructed of cast-iron or hard bronze. Around 50 the rim of the disk are placed the words "Press hard." I prefer this form of spring to that described in my specification for Letters

Patent, numbered 392,641, issued November 5, 1888, to which Letters Patent and the specification thereto annexed I would refer for a 55 more particular description of my auxiliary alarm-box.

c' designates a curtain which covers the push-button, and is exposed to view when the disk is pressed in and falls to the bottom of the 60 box. On this curtain are printed the words "Alarm sent in," my purpose being to remove all temptation after sending in an alarm to tamper with the box. The action on the push-button by the disk, on account 65 of the force necessary to send the disk inward and its sudden release from the disk-holding spring, is very positive and removes all liability of failure to send in an alarm.

In Figs. 1, 2, and 3, B designates a metal 70 arm secured in a slot of the push-button S by the set-screw b^2 . c designates an electrically-connected lever, termed the "general contact-lever," which is pivoted to the insulated screw a' . The lever c has a right-angled arm, 75 Fig. 2, extending from the fulcrum and pivoted to the connecting-bar c^2 by means of the screw c^3 , and the connecting-bar c^2 is jointed to the free end of the local contact-lever D , the said lever being pivoted to the insulated 80 post d , which is secured to the back of the box. e designates a local contact-clamp secured to the box by the insulated post e' . From the posts d and e' electric connection is 85 made with the battery G , which serves to operate the gongs $g g$, set in the various departments and also the gong g' at the outside of the building. The battery G is also connected with the various auxiliary stations A in the several departments. When the disk a is 90 pressed inward, sending the alarm to the general station A' , as explained in my Letters Patent before referred to, by the same movement the arm B is forced against the side of the opening c^4 in the long arm of the lever c . 95 This lever forms a passing electric contact with the projecting bend b^3 of the spring r^2 , which when in engagement with the lever is forced into contact with the electrically connected and insulated post p^2 , which forms a 100 part of the electric circuit T to the general-alarm station A' , and also serves to carry the free end of the lever D into the clamp e . The lever D is connected with the battery G

by means of a wire passing into the insulated post d . Now as soon as the contact is formed between the lever D and the clamp e , which, as described, is connected by a wire s^2 with 5 the gongs $g g$, the gongs in the various departments ring a continuous alarm, since the contact can only be broken by opening the alarm-box and replacing the levers in their original positions.

10 h designates an intermediate lever which loosely enters a slot c^5 in the connecting-bar c^2 , the said lever being pivoted upon the stud f , which may either be secured to the box or to the wall of the apartment.

15 h^3 designates a connecting bar or chain extending downward from the outer end of the lever h to the end of the lever h^4 , which is pivoted to the stud p . The lever h^4 is provided with a detent-pin p' , which engages

20 with a tooth s^3 on the periphery of the wheel K . Upon this wheel is wound a chain b^3 , having a weight L attached to the end thereof. When the detent-pin p' is raised from the tooth s^3 in the wheel K , the weight L will 25 fall, causing the wheel to revolve, and this revolution opens a valve M in the elbow s of the pipe P , this valve forming a cut-off between the main pipe P and the feed-pipe P' .

The main pipe P may be connected with 30 any proper water-supply, and the water from the same will be distributed through the several departments by means of the distributing or feed pipe P' , connected with the main pipe P , as described. At regular intervals in 35 the feed-pipe P' , I would place distributing heads or sprinklers $v v$.

It will readily appear from my description that by a single pressure upon the disk a of either of the auxiliary stations $A A A$ an 40 alarm will be sent into the general station A' , and that by the same movement a continuous alarm will be given to the occupants of the various departments connected by my auxiliary stations.

45 I have also incorporated into my system an automatic alarm and an automatic extinguisher, which I explain as follows: Immediately beneath the ceilings of the several departments in which my auxiliary stations are placed, or in any desired location, I would 50 suspend by the pulleys y a cable R , constructed in adjoining alternate sections of an easily-fusible metal wire chain a^4 and a combustible cord a^5 , preferably of cotton. The 55 cable R is attached to the weighted lever r , the said lever being pivoted to the stud r' , which is secured to the wall and connected to a bar or chain r^4 , which is attached to the lever h . I employ this construction of alternate sections of wire chain and cord in order 60 that in any room in which the fire may be, if the heat should fail to reach and melt the fusible chain, yet the flame, by contact with the cord, will cause the separation of the cable. 65 As soon as the cable for any reason becomes disunited the weight L' carries down with itself the end of the lever r , thus lifting the

chain r^4 , which in turn raises the detent-lever from the wheel K , and thus opens the water-valve from the main to the distributing 70 pipes. By the same movement the outer end of the lever h will be raised and the inner end within the station-box depressed, and, as before described, an alarm will be sent to the general station A' , and a contact will be made 75 between the electrically-connected lever D and the insulated clamp e , which is connected with the gongs $g g$, thus automatically ringing a continuous alarm and distributing the water automatically at the same time. 80

There is one feature of my invention to which I would direct attention, viz: it will be observed that when the cable is for any reason disunited, and by that means the long arm of the lever c carried forward, a proper 85 contact will be made with the electrically connected and insulated post p^2 , by means of which an alarm will be sent into the main or central station automatically, and at the same time a local alarm will be rung continuously 90 at g' on the outside of the building, indicating the building on fire, thus doing away with the necessity of sending a messenger to the alarm-box or general station A' to direct the firemen to the proper building, and by 95 reason of the slot c^4 , which allows a forward movement of the lever c independently of the arm B of the push-button, a subsequent 100 alarm can be sent into the general station by forcing the disk a inward against the push-button S , so as to form a contact between the insulated spring a^6 and the insulated plate a^7 , thus again closing the circuit T to the main station.

I claim as my invention—

1. The combination of the metal disk, the caliper-formed spring for holding the same, and the electrically connected and adjusted push-button, substantially as and for the purpose described. 105

2. The combination of the metal disk, a spring for holding the same, the electrically connected and adjusted push-button, and a curtain secured to the box and covering said push-button, substantially as and for the purpose described. 110

3. The combination, with the metal disk, a spring for holding the same, the electrically connected and adjusted push-button provided with the projecting arm, and the general contact-lever loosely engaged with the arm of the push-button, of the local contact-lever connected with the general contact-lever, and the local contact-clamp electrically connected with the gongs, substantially as described. 115

4. In an auxiliary fire alarm and extinguisher, the combination, with the metal disk, a spring for holding the same, and the electrically connected and adjusted push-button provided with the projecting arm, of the general contact-lever loosely engaged with the projecting arm, the connecting-bar jointed to the general contact-lever, the intermediate lever jointed to the connecting-bar, the detent-lever con-

neected with the intermediate lever, the weight-
ed wheel engaging with the detent-lever and
conected with a valve between the main pipe
and the distributing-pipe, and the distribut-
5 ing-heads for the water, whereby upon raising
the detent-lever the water will be sprinkled
from the heads and an alarm will be sounded
at the general station and a second alarm can
be sent to the said station, substantially as
10 described.

5. In an auxiliary fire alarm and extin-
guisher, the combination, with a cable consist-
ing of alternate sections of combustible and
fusible material, of a weighted lever attached
15 to the said cable, the detent-lever connected
with the weighted lever, and a weighted wheel
adapted to engage with the detent-lever and
connected with the valve between the main
and distributing pipes, whereby when the
20 said cable becomes disunited the valve will
be opened automatically, substantially as de-
scribed.

6. In an auxiliary fire alarm and extin-
guisher, the combination, with a cable consist-
ing of alternate sections of combustible and 25
fusible material, of a weighted lever attached
to the cable and connected with the interme-
diate lever, which extends into the interior of
the station-box and is connected with both
the general contact-lever and the local con-
30 tact-lever of the station-box, whereby when
the cable becomes disunited the dropping of
the weighted lever will cause the raising of
the intermediate lever, the electric engage-
ment of the local contact-lever to ring the 35
gongs, and the electric engagement of the gen-
eral contact-lever to send an alarm to the
general station and also permitting the send-
ing in of a second alarm to the general sta-
tion, substantially as described.

EASON L. SLOCUM.
